UNITED STATES PATENT OFFICE.

JOHN HUME BELL, OF EAST ORANGE, NEW JERSEY, ASSIGNOR TO WESTERN ELECTRIC COMPANY, INCORPORATED, OF NEW YORK, N. Y., A CORPORATION OF NEW YORK.

SELECTIVE SYSTEM.

1,387,228.

Specification of Letters Patent.

Patented Aug. 9, 1921.

Application filed July 26, 1917. Serial No. 182,961.

To all whom it may concern:

Be it known that I, JOHN H. BELL, a citizen of the United States, residing at East Orange, in the county of Essex and State of New Jersey, have invented certain new and useful Improvements in Selective Systems, of which the following is a full, clear, concise, and exact description.

This invention relates to selective systems, and more particularly it relates to a selective system for use in printing telegraphs and the like.

Its object is to provide an arrangement which is adapted to use with a three-unit code, and one which may, therefore, be employed economically in connection with expensive line conductors, such as submarine cables.

In accordance with this invention three line relays are provided and connected to the line circuit. One of these relays is responsive to all impulses in the line circuit regardless of the strength or polarity thereof. The second and third relays are selectively responsive to impulses of strong positive or negative current respectively. A contact making device, having a plurality of contacts and a movable contact member, such as a rotary distributor, serves to connect one of several groups or relays to the tongue of the first relay, with each impulse of current in the line circuit. From here on individual circuits extend from each relay in the group to the contacts of the second and third line relays. The connections to these contacts are such that not more than one relay in a group can be energized at a time. The distributor and line relays therefore coöperate to give an indication of the character of the line impulses, by setting up a combination in the relays characteristic of the particular signal received. A holding circuit is provided which retains the combinations set up for a predetermined length of time.

This arrangement may easily be applied to printing telegraph systems, one method being to have the relays set up various combinations in an electromechanical selecting system, which would allow the printing of a certain letter or character for each combination set up. The relays themselves might

perform this function, or they might be caused to control energizing circuits for electromagnetic devices, as shown on the accompanying drawing, and these devices in turn set up the combination.

The above and other objects of this invention will be fully set forth in the following description and claims, and will be more readily understood by reference to the accompanying drawing, which shows a diagrammatic representation of the apparatus and system of connections.

The line L is connected to ground through the windings of three relays, 1, 2, and 3. Relay 1 is a polarized relay, and responds to all impulses of current in the line circuit, the tongue 4 connecting with the contact 5 for each impulse of positive current, and with the contact 6 for each impulse of negative current. Relays 2 and 3 are biased to respond to impulses of strong positive or negative current, respectively. The tongue 4 of relay 1 is electrically connected to the contact arm 7 of a distributor 8 by means of a collector ring 9. Contact arm 7 is adapted to make connection with segments 10, 11 and 12, etc., of the distributor 8.

In order to simplify the description and avoid confusion by multiplicity of parts on the drawing, only one group of receiving equipment is shown connected to the distributor 8. It is obvious, however, that other groups of receiving equipment may be thus connected to the idle segments of the distributor, so that a number of receiving instruments may be operated to receive several distant messages being transmitted over the line conductor L.

The segments 10, 11 and 12 of the distributor 8 are connected by means of the conductors 13, 14 and 15 with three groups of relays; conductor 13 being connected to relays 16, 17 and 18, conductor 14 to relays 19, 20 and 21, and conductor 15 to relay 22. From here on, each individual relay is connected to one of three conductors which terminate respectively at the contacts 23 and 24 of relay 2, and contact 25 of relay 3. For example, relay 16 is connected to conductor 26 which terminates at contact 24; relay 17 is connected to conductor 27 which terminates at contact 23, and relay 18 is

connected to conductor 28 which terminates at contact 25. Each relay in these groups is provided with an armature having two contacts which close when the relay is energized.

5 A common lock-up circuit is connected to the contact 29 of each relay and serves to hold the relay in the energized position after it has been actuated. The lock-up circuit may be traced from the battery 30, conductor 31, point 32, armature 33 and back contact 34 of cut-off relay 35, common conductor 36 to the lock-up windings 37 and contacts 29 of relays 16 to 22, through the armatures 38 of relays 16 to 22, to the common conductor 39, point 40; and return over conductor 41 to the battery 30.

The drawing shows electromagnetic devices 42 to 48 one of which is individual to each relay, with an energizing circuit 20 which is completed by the closing of the second contact 68 when the relay is actuated. These electromagnetic devices 42 to 48 may be the selecting magnets of a receiving printer similar, for example, to that shown 25 in Dixon Patent No. 1,201,809, or they may be omitted entirely, the relays 16 to 22 themselves performing the function of selecting magnets.

A better understanding of the system may 30 be had by following the various operations that take place upon the receipt of a signal, and for the purpose of illustration, let it be assumed that impulses corresponding to the letter "A" are to be transmitted, and let it 35 further be assumed that the first impulse is strong positive current, the second weak negative current and the third weak positive current.

The arm 7 of the distributor or switching 40 means 8 is rotated at a constant speed by any suitable means (not shown), and is kept in synchronism with a similar sending distributor by any of the methods well known in the art. Thus, when the first impulse is 45 received the arm 7 will be in contact with segment 10, when the second impulse is received the arm 7 will be in contact with segment 11, etc. The first impulse being strong positive, the tongue 4 of the relay 1 is moved to the right and connects with the contact 5; and the tongue 49 of the relay 2 is moved to the left and connects with the contact 24; relay 3 remains inoperative. Current then flows from the battery 30 by way 55 of conductor 31, point 50, contact 5, tongue 4 of relay 1 to collector ring 9, contact arm 7, segment 10, conductor 13, point 70, winding 51 of relay 16, conductor 26, contact 24 and tongue 49 of relay 2 and back over conductor 60 41 to the battery 30. Armature 38 of relay 16 is therefore pulled up and contacts 52 are closed. This locks up relay 16 by energizing the winding 37. This circuit is traced from the battery 30, conductor 31, point 32, armature 33 and contacts 34 of cut-off relay

35, conductor 36, winding 37, contact 29, and armature 38 of relay 16, conductor 39, point 40, and return over conductor 41 to the battery 30. Electromagnetic device 42 is now energized by the current from battery 30, 70 conductor 31, point 53, magnet 42, conductor 55, contacts 52 and 68 of relay 16, conductor 39, point 40 and conductor 41. This completes the reception of the first impulse, and relay 16 remains in a locked position as the 75 arm 7 of the distributor 8 passes on to segment 11.

Upon reaching segment 11, the second impulse (weak negative current) is received. This moves the tongue 4 of the relay 1 to the left, making connection with contact 6, and relays 2 and 3 remain inoperative. It will be observed that no relay in the second group will respond to this impulse, for the negative pole of the battery 30 is now connected to the second group comprising relays 19, 20 and 21 by way of the distributor 8 and contact 6 of relay 1, and no connection can be had to the positive side of the battery 30, for contacts 24 of relay 2 and contacts 25 90 of relay 3 are open, and contact 23 of relay 2 is connected to the negative side of the battery 30.

It is obvious that the tongues of the relays or impulse receiving units 1, 2 and 3 will 95 assume the above position with all weak negative impulses, and that none of the relays 16 to 22 will be energized by impulses of this character, regardless of which group is connected to the distributor at the time 100 the impulse is received.

The arm 7 of the distributor 8 has now passed on to the next segment 12 as the third impulse (weak positive current) is received. This moves the tongue 4 of the relay 1 to the right, making connection with the contact 5 and the relays 2 and 3 remain inoperative. Current now flows from the battery 30 by way of conductor 31, point 50, contact 5 and tongue 4 of relay 1 to collector ring 9, 110 contact arm 7, segment 12, conductor 15, winding 56 of relay 22, point 57, conductor 27, contact 23, and tongue 49 of relay 2 and return over conductor 41 to the battery 30. The armature 38 of the relay 22 is pulled 115 up and locked in position, and the electromagnetic device 48 is energized, in the same manner as took place for relay 16 when the first impulse was received.

By means of auxiliary equipment associated with the receiving apparatus (not shown on the drawing), the printing of a certain letter or character, determined by the energization of electromagnetic devices 42 and 48, takes place; after which the cut-off relay 35 is energized by the closing of a circuit by the distributor 8. This circuit may be traced from battery 58, conductor 59, segment 60, arm 7 of distributor 8, segment 61, conductor 62, the winding of cut- 130

off relay 35, and return over conductor 64 to the battery 58. The energization of cut-off relay 35 opens the contact 34 in the lock-up circuit and allows relays 16 and 22 and 5 their associated electromagnetic devices 42 and 48 to return to their normal position.

Without going into a further detailed description of the various operations that take place upon the receipt of a signal whose impulses are of a different character from those 10 above selected for illustration, it will be observed by reference to the drawing, that two relays 16 and 19 are caused to operate by impulses of strong positive current in the 15 line circuit L, two relays 18 and 21 by impulses of strong negative current, and three relays 17, 20 and 22 by impulses of weak positive current. Impulses of weak negative current have no effect upon the receiving 20 apparatus in so far as their influence affects the operation of any of the relays. They do, however, cause the tongue 4 of the relay 1 to close against contact 6 which is connected to the negative pole of the battery 25 30, but no return path to the positive pole of the battery 30 is provided, for the tongue 49 of relay 2 is also connected to the negative side, and the contact 25 of relay 3 is open.

What is claimed is:

30 1. In a telegraph system, a line, a plurality of impulse receiving relays serially connected with said line, a plurality of selecting relays, a source of potential, and means for consecutively connecting said

35 source of potential with said selecting relays upon the energization of a pair of said impulse receiving relays for causing the operation of said selecting relays.

2. In a telegraph receiving system, a first 40 and a second line relay, a plurality of selecting relays connected in a first order of grouping with respect to control by said line relays, distributor means connected in a second order of grouping with respect to control of said selecting relays, a source of current, and a third line relay to coöperate with said distributor in energizing individual relays of said groups as selected by said first and second line relays.

50 3. In a signaling system wherein the various characters of a message are represented by impulses of different intensities of positive or negative current, a receiving means comprising a line relay responsive to all impulses of current in the line circuit, a local circuit including the tongue of said line relay, a distributor adapted to connect the tongue of said line relay successively to each of a plurality of segments of said distributor, 55 a group of relays individual to each segment of said distributor, and selecting relays responsive to impulses of a certain character in the line circuit, said selecting relays coöperating with said distributor and said

line relay to complete said local circuit to 65 not more than one relay in each of said groups.

4. In a telegraph system, a line, a plurality of impulse receiving relays connected with said line, a plurality of selecting relays, a source of potential, and a rotary distributor for establishing an energizing circuit for said selecting relays directly through contacts operated by a pair of said impulse receiving relays. 70 75

5. In a telegraph receiving system, a plurality of groups of selecting relays, a source of current, a line relay responsive to line current impulses for partly establishing a circuit between said selecting relays and source of current, additional line relays responsive to current impulses of predetermined strength and polarity for selecting one of said groups of relays, and rotary distributor means for completing the partly established circuit to energize a selected one 80 85 of said relays.

6. In a telegraph receiving system, a plurality of groups of selecting relays, distributor means, a source of current, a first line 90 relay to coöperate with said distributor in applying said source of current to said groups of relays, a second and third line relay for selecting relays in said groups, and interconnections between said line relays to 95 enable said distributor to effect operation of selected ones of the relays of said plurality of groups.

7. In a telegraph receiving system, three polarized line relays, a first and a second 100 group of selecting relays, a source of current, rotary distributor means to coöperate with said line relays in applying said current to said selecting relays, and interconnections under the sole control of two of 105 said line relays to disable the relays of one group while enabling operation of the relays of the other group.

8. In a telegraph system, a plurality of impulse receiving relays, a plurality of selecting relays, a distributor, and an energizing circuit for said selecting relays completed through the contacts of said impulse receiving relays and said distributor, and rendered ineffective due to the energization 110 of said receiving relays by the transmission of a certain group of impulses over said line. 115

9. In a telegraph receiving system, a source of current, a plurality of polarized line relays, a plurality of groups of selecting relays, distributor means to serve jointly with said line relays in applying the current to said groups of selecting relays, and interconnections under the sole control of two of said relays to limit said applications 120 of current to the operation of one relay only in said groups of selecting relays at one and the same time. 125

10. In a telegraph receiving system, a plurality of polarized line relays, a plurality of selecting relays, distributor means, interconnections to establish said selecting relays in groups of three relays with respect to control by said polarized relays, a source of current, means jointly controlled by said

relays and said distributor for applying said current to a single relay of each group, and means controlled by said distributor for disabling each group of said selecting relays. 10

In witness whereof, I hereunto subscribe my name this 21st day of July A. D., 1917.

JOHN HUME BELL.
